CLAIM

The ornamental design for a flower pot column as shown.

DESCRIPTION

FIG. 1 is a front, left, and top perspective view of a flower pot column, showing my new design;

FIG. 2 is a rear, right, and bottom elevation view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of an encircled area labeled "9" in FIG. 2;

FIG. 10 is a front, left, and top perspective view of a second embodiment of the flower pot column;

FIG. 11 is rear, right, and bottom perspective view of FIG. 10;

FIG. 12 is a front elevation view of FIG. 10;

FIG. 13 is a rear elevation view of FIG. 10;

FIG. 14 is a left side elevation view of FIG. 10;

FIG. 15 is a right side elevation view of FIG. 10;

FIG. 16 is a top plan view of FIG. 10;

FIG. 17 is a bottom plan view of FIG. 10; and,

FIG. 18 is an enlarged view of an encircled area labeled "18" in FIG. 11.

The dot-dash broken lines, as shown in FIGS. 2, 9, 11, and 18 framing portions of the flower pot column for enlargements purposes, form no part of the claimed design.

1 Claim, 18 Drawing Sheets
